[57] ABSTRACT

An electron lens transmitting a plurality of electron beams from a source thereof to converge at different points on a screen whereby aberrations are caused to occur thereat, and each of two electrodes included in the lens are formed with spaced elongated openings of preselected configurations and predetermined dimensions in electrode sections adjacent to spaced peripheries of the electron lens for transmitting the respective beams through the peripheral openings in the respective electrodes to converge at a common point on the screen to minimize aberrations thereat.

ELECTRON LENS FOR CONVERGENCE OF PLURALITY OF BEAMS

BACKGROUND DESCRIPTION OF THE INVENTION

This invention relates to an electron lens used for electron discharge devices, and more specifically to an electron lens used for color television picture tubes.

In the conventional electrostatic electron lens, the farther the electron beam is away from the center axis of the electron lens, the greater becomes the aberration. In such electron lens used in a cathode-ray tube, the electron spot coming out on the fluorescent screen spreads with a considerable amount of distortion when the electron beam is passed through the outer portion of the electron lens. This results in loose resolution and has made the electron lens impracticable. In order to avoid the above-mentioned difficulties, the color television picture tube, for example, which is to require a plurality of electron beams has hitherto been provided with as many electron lenses as the electron beams used, so that each electron beam may pass through the center portion of each electron lens, or has been provided with one electron lens so designed that all the electron beams may pass through the center portion of the electron lens or otherwise the diameters of the electron lens must be increased. To realize these, however, design difficulties have been inevitable.

The object of this invention is to provide an electrostatic electron lens, which with only little aberration, converges the electron beams passing through its edge portion.

An electron lens embodying this invention has as its element such an electrode as having at least one elongated opening whose longitudinal direction is perpendicular to both the radial direction and the center axis of the electrode, in order that the electron beam off the center axis passes through said openings. (Note: Said perpendicular direction will hereinafter be called "lateral direction").

The elongated opening disposed in the electrode of the electron lens according to this invention serves as a diverging lens having a relatively strong diverging effect in the radial direction of the electrode and a relatively weak diverging effect in the lateral direction, to compensate the aberration in the electron lens.

Assume that a small circular hole is disposed in a metal plate having an electric potential of V , and an electron beam perpendicular to the metal plate passes through the hole, and that the electron beam advances in the positive direction. Then the focal distance f_1 of the electron lens formed by the circular hole is expressed as:

$$f_1 = 4V/(E_1 - E_2) \quad (1)$$

where

E_1 is an electric field on the side from which the electron beam enters the circular hole.

E_2 is an electric field on the side to which the electron beam comes out of the circular hole.

When, instead of the small circular hole, a straight slit is disposed therein, the focal distance with respect to the focusing action in the longitudinal direction of the slit is infinite. The focal distance f_2 with respect to the focusing action in the transverse direction of the slit is expressed by the following equation when the potential V and electric fields E_1 and E_2 are the same as above.

$$f_2 = 2V/(E_1 - E_2) \quad (2)$$

In other words, the focal distance of the slit is half that of the circular hole, and if E_2 is larger than E_1 in either case, then the focal distance will be negative and the small circular hole or the thin opening will work as a diverging lens.

The elongated opening becomes nearly circular or to be able to be considered as a circular hole, as the value of the length-breadth ratio of the elongated opening approaches 1. While, the elongated opening becomes a slit as the length-breadth ratio increases. Hence, by suitably selecting the length-breadth ratio, the focal distance of the elongated open-

ing with respect to its length direction can be determined to a value between infinity and f_1 , and that with respect to the breadth direction can be determined to a value between f_2 and f_1 , which are given by above equations (1) and (2). This teaches us that the elongated opening, when used as a diverging lens, shows a stronger diverging effect in the transverse direction than in the longitudinal direction, and that the diverging effect can be varied to a considerable extent by changing the length-breadth ratio of the elongated opening.

- 10 The electron converging lens in general has such aberration that the converging effect on the electron beam passing through the outer portion of the electron lens is stronger in the radial direction than in the lateral direction of the lens. On the other hand, according to this invention, an excessively strong 15 converging effect in the radial direction of the electron lens can be compensated by a relatively strong diverging effect in the transverse direction of the elongated opening. In other words, by suitably determining the length-breadth ratio of the elongated opening and thus suitably compensating the converging effect, it becomes possible to minimize the aberration in the lens.

FIG. 1 is an optical model diagram illustrating the aberration in a conventional electron lens;

- 20 FIG. 2 is an optical model diagram illustrating the principles of the present invention;

FIG. 3 is an axial sectional diagram showing a specific embodiment of the invention; and

- 25 FIGS. 4, 5 and 6 are plan views of components usable in FIG. 3.

DETAILED DESCRIPTION

The invention will be explained in detail by referring to the appended drawings.

- 30 FIG. 1 illustrates an optical model of a conventional electron lens and some electron beams passing through the edge portion of the lens, wherein light rays 13, 14 and 15 parallel to the principal axis 12, after passing through a convex lens 11, and cross the principal axis 12 at points 13', 14' and 15'. This takes place due to the well-known spherical aberration and has been thought unavoidable in the conventional electron lens. A light beam having a circular section 16' on the plane 16 comes out to cast its cross section 17', 18' and 19' on the planes 17, 18 and 19, respectively, being refracted through the lens 11. As a result, the light beam spot appears in a considerably distorted and spread shape. In view of the cross section 17' on the plane 17, the lens 11 has evidently a stronger converging effect in its radial direction than in its lateral direction.

- 35 FIG. 2 is an optical model showing the principles of this invention. In FIG. 2 light rays 24, 25 and 26 parallel to the principal axis 22 and incident upon the convex lens 21, respectively, are shown as an optical model of electron rays passing 40 through the edge portion of an electron lens. Also, in FIG. 2 a concave lens 23 having a stronger diverging effect in the direction parallel to the plane of the drawing than in the direction perpendicular to the plane of the drawing is shown 45 as an optical model regarding the elongated opening of this invention. Relating the optical model of FIG. 2 the light rays 24, 25 and 26 are suitably diverged and compensated by the concave lens 23 in the radial direction of the convex lens 21 and then are converged by the convex lens 21. As a result, the 50 light rays 24, 25 and 26 are focused nearly at the point 28 on the principal axis 22, and a light beam having a circular section 27' on the plane 27 comes out as a very small converged light beam having a cross section 28' on the plane 28.

- 55 FIG. 3 is to illustrate the first embodiment of this invention. In FIG. 3 an electron beam from the triode part consisting of a cathode electrode 301, a first grid electrode 302 and a second grid electrode 303 is moderately converged by a prefocus lens 60 part formed between the second grid electrode 303 and third grid electrode 304. Then, the electron beam, after passing 65 through the elongated opening 305 disposed in the third grid

electrode 304, enters the main lens part formed by the third grid electrode 304, fourth grid electrode 306 and fifth grid electrode 307. The main lens part is of so-called unipotential lens type, and a positive high voltage is applied to the third grid electrode 304 and fifth grid electrode 307, while, the fourth grid electrode 306 is held at nearly zero potential. When the forward direction of the electron beam 310 is assumed positive, the electric field strength on the left of the elongated opening 305 of the third grid electrode 304 is negative and relatively small and that on the right is positive and relatively large. Therefore, the elongated opening 305 operates as a diverging lens. The electric field on the left of the elongated opening 308 disposed in the fifth grid electrode 307 is negative and relatively large, and that on the right is nearly zero. Therefore, the elongated opening 308 operates also as a diverging lens. In FIG.2 one diverging lens is used for compensation purpose. While, in the embodiment as in FIG.3, the both elongated openings 305 and 308 are used and have a diverging effect for compensation so that even strong aberration may be compensated. Accordingly, the main lens part may operate with little aberration and good converging effect on the electron beam 310 passing through the edge portion of the main lens. As a result, the electron beam 310 comes out as a sufficiently small electron spot on the fluorescent screen 309. In FIG. 3, only one electron beam 310 is shown. Practically, however, three electron beams having circular sections (the lateral section of these electron beams are positioned at the vertex of an equilateral triangle) are used in the color television picture tube and, therefore, three pairs of elongated openings 305 and 308 must be provided.

FIG. 4 shows an arrangement of three elongated openings. These openings 42 are disposed so that their longitudinal directions are coincident with the lateral direction of the electrode 41. It is necessary to suitably determine the length-breadth ratio of the elongated opening 42 for effective aberration compensation. It is also necessary to determine the breadth (the narrower one of the distances across the opening) to be wide enough to pass the electron beam.

FIG.5 shows the third and fifth grid electrodes of the second embodiment of the invention. These electrodes 51 are provided with arc shaped elongated openings 52 which are disposed along the circumference of the electrodes.

These arc-shaped elongated openings have nearly the same aberration compensating effect as the straight elongated opening. The arrangement in FIG.5 is characterized in that there will be little deviation in the positional relationship between the electron beam and the elongated opening even if a small amount of error is caused in the lateral direction in the electrode assembly process.

FIG. 6 is to illustrate the third embodiment of the invention, wherein each of the third and fifth grid electrodes 61 is provided with a circular hole 62 in the center, and also with arc-shaped elongated openings 63 disposed on the outer side of the circular hole 62. This embodiment is an example applied to the color television picture tube of so-called in-line type in which the lateral sections of three electron beams are aligned at equal intervals on one straight line. According to this embodiment, the hole in the center is circular because the center electron beam passes through the center of the electron lens to cause little aberration and no compensation on aberration is needed.

In the foregoing embodiments, the unipotential lens is employed. Instead, other types of lenses, for example, bipotential lens, may be used for aberration compensation according to this invention.

While a few embodiments of the invention have been described, it is particularly understood that invention is not limited thereto or thereby.

What is claimed is:

1. A cathode-ray tube comprising in combination: means producing a plurality of electron beams; a screen receiving said beams; a plurality of hollow electrodes separated by an open ended cylindrical electrode and spaced in tandem between said beam means and screen whereby said screen and electrodes are provided with a common center axis; said electrodes energized with electric potentials of predetermined magnitudes for transmitting said beams therethrough on further axes spaced from said center axis to incidence with said center axis at points off said screen to cause an aberration of said beams at said screen; and means compensating for said aberration, including first and second of said electrodes provided with mutually opposing closed ends disposed perpendicularly to and coaxial with said center axis, each of said ends formed with elongated openings equal in number to the number of said beams, each opening receiving a corresponding beam, and spaced from said center axis and provided with a preselected configuration, said openings having preassigned maximum and minimum dimensions of which said minimum dimension is disposed in a radial direction relative to said center axis for transmitting all electrons of said respective beams said openings aligned in one plane for transmitting said respective beams to move said points to incidence with said center axis at said screen to compensate for said aberration.

2. The cathode-ray tube according to claim 1 in which said openings have preselected rectilinear configurations.

3. The cathode-ray tube according to claim 1 in which said openings have preselected curvilinear configurations.

4. A cathode-ray tube comprising in combination: a screen receiving a plurality of electron beams; means producing said plurality of electron beams of which a central one has an axis coincident with a center axis of said screen,

a plurality of hollow electrodes separated by an open ended cylindrical electrode and spaced in tandem between said beam means and screen whereby said electrodes are provided with an axis coincident with said one beam and screen axis; said electrodes energized with electric potentials of predetermined magnitudes for transmitting another of said beams through said electrodes on a further axis spaced from said electrode axis to incidence with said screen axis at a first point off said screen to cause an aberration of said another beam; and

means compensating for said aberration, including first and second of said electrodes provided with mutually opposing closed ends disposed perpendicularly to and coaxially with said electrode axis; each of said ends formed with a central opening coaxial with said screen, one beam and electrode coincident axes for transmitting all electrons of said central one beam and with at least one elongated opening spaced from said electrode axis and having maximum and minimum dimensions of which said minimum dimension is disposed in a radial direction relative to said electrode axis for transmitting all electrons of said another beam; said elongated openings aligned in one plane for transmitting said another beam to move said first incident point to coincidence with said screen axis at said screen to compensate for said aberration.
